ATTACHMENT FOR MICROSCOPES

Lloyd R. Bowen, Oakland, Calif.

Application November 6, 1937, Serial No. 173,145

1 Claim. (Cl. 88—40)

This invention relates to an attachment for microscopes or refractometers, particularly useful in bacteriological research.

It is an object of the invention to provide apparatus for maintaining the culture under observation, when in the microscope or refractometer at a predetermined uniform temperature.

Another object of the invention is to provide a small but efficient apparatus for heating and 10 circulating fluids.

The invention possesses other objects and features of advantage, some of which, together with the foregoing, will be specifically set forth in the specification hereunto annexed. It is to be understood that the invention is not to be limited to the particular species thereof shown and described as various other embodiments thereof may be employed within the scope of the appended claim.

20 Referring to the drawing:

Figure 1 is a view, partly in perspective, partly in front elevation and partly in vertical section, showing the apparatus of my invention connected for use with a refractometer.

25 Figure 2 is a perspective view of the heat radiator.

Figure 3 is a bottom elevational view looking upwardly into the pump casing. The plane in which the view is taken is indicated by the line 30 3—3 of Figure 1.

There are, as is generally known, certain types of bacteria which attain their greatest activity only in temperatures which approach that of the human body and are therefore considerably above the usual temperature of the laboratory. In order to provide the temperature best suited to the particular organism, so that it may be studied under the most favorable conditions, it is obviously not economical to heat the entire laboratory to the temperature desired as this might adversely affect other observations or experiments being simultaneously carried on. The solution therefore, is to apply local heat to the specimen and this has been done before in several different ways. One of the most widely used of these methods is to provide a hollow metal shell, which is placed on the slide rest of the microscope or refractometer, through which warm water may be circulated. The slide bearing 40 the specimen to be studied is placed on this shell and the heat radiated from the circulating water will keep the specimen warm. This heat however, is not sufficiently uniform to insure the best results for the reason that the warm water is 50 usually obtained from the hot water mains of the

building and as the flow of water through the shell depends on the pressure of the mains, considerable fluctuation of flow occurs as more or less water is drawn from the mains in other parts of the building. These variations in flow will obviously affect the temperature with the result that constant vigilance is necessary to maintain the specimen at the desired degree of heat.

5 In addition to the above there is another undesirable feature connected with the use of water from the building mains to heat the specimen and that is that scale or other sediment may find its way into the shell or the conduits connected thereto and clog them thereby preventing the free flow of water therethrough.

10 I have provided apparatus by means of which a quantity of water at a constant temperature and volume may be circulated through a heat radiator adapted to be mounted on the microscope or refractometer and I have also provided 15 in this apparatus an improved radiator and a simple and efficient means for circulating the water.

15 In detail, I provide a heat radiator, shown in detail in Figure 2, comprising a hollow rectangular shell 4 composed of glass, Celluloid or other transparent material, which is adapted to be placed on the slide support 6 of the microscope 7 and held in place thereon by the usual spring clips 8, and between the upper surface of the 20 radiator and the clips may be placed the slide 9 carrying the specimen to be observed. The radiator is composed of transparent material so that, if desired, light may be directed upwardly 25 through both the radiator and slide by the mirror reflector 11. Hollow nipples 12 are attached to, and at each end of, the radiator, to each of which is connected a rubber conduit 13.

25 A heater is provided which may be a conventional electric plate 14, having a heating element 15, therein which is connected by a cord 16 to a source of current. The connector plug 17 has therein a rheostat adjustable by means of the knob 18 so that the current flowing through the heating element 15 may be controlled to govern 30 the temperature radiated by the plate. On the plate is disposed a vessel 19, preferably composed of glass or other such material, containing a quantity of water 21.

35 A pump is provided, immersed in the water in 50 the vessel 19, by means of which the water may be circulated through the heat radiator 4. The pump comprises a substantially rectangular base plate 22 having at each corner thereof a rubber foot 23 which spaces the plate from the bottom 55

of the vessel 19 as shown in Figure 1. A pump housing 24 is provided with a recess which, when the housing is attached to the base plate by the screws 26, forms a chamber 27. Mounted for 5 rotation with the shaft 28, and positioned concentrically with the axis of the chamber, is a vaned runner 29 which is driven by a miniature induction motor 31 supported above the housing 24 by the posts 32. As is shown in Figure 3, the 10 chamber 27 has a recess 33 therein into which opens the lower end of a discharge conduit 34 which is soldered or otherwise secured to the housing and the upper end of which is connected to one of the rubber conduits 13. The other or 15 return conduit 13 is attached to a U-shaped pipe 36 which may be hung over the rim of the vessel 19 to discharge the water flowing therein into the vessel. The water in the vessel is admitted into the pump chamber through a suction inlet 20 provided in the base plate which comprises an aperture 37 located concentrically with the axis of rotation of the runner 29, and provided with a marginal flange 38 which projects upwardly into the chamber. As will be seen in Figure 1 the 25 vanes of the runner are cut away to clear this flange. The provision of the flange about the suction aperture effects a material reduction in the "slippage" of the pump since it prevents water in the lower part of the chamber from flowing out of the chamber through the suction aperture.

When the pump is running, the water drawn into the pump chamber will be forced by the vaned runner out through the discharge conduit into one of the rubber conduits 13, through the heat manifold 4, back through the other rubber conduit 13, and into the vessel 19 through the pipe 36. The temperature of the water may be very accurately controlled by adjusting the rheostat 17 to govern the amount of current flowing 10 through the heater 15.

It is apparent that the apparatus just described is capable of performing functions about the laboratory other than that just described. By dispensing with the heat radiator 4 the pump may 15 be used to add or withdraw fluids to or from containers, and by removing the pump from the vessel 19 the pump may be used as a pressure blower, for aeration or the like, or as a vacuum pump.

I claim:

An attachment for use with a microscope, a 20 relatively thin narrow hollow rectangular shell having parallel upper and lower walls adapted to fit within and be held by the slide support of the microscope, said shell formed in one piece 25 and of transparent material, and nipples at opposite ends of said shell to permit of the passage of fluid through said shell.

LLOYD R. BOWEN.
